[57] CLAIM

The ornamental design for a garment protector, as
shown and described.

DESCRIPTION

FIG. 1 is a right side elevational view of a garment
protector showing my new design.

FIG. 2 is a frontal view as seen looking in the direction
of arrows 2—2 of FIG. 1.

FIG. 3 is a rear view as seen looking in the direction of
arrows 3—3 in FIG. 1.

FIG. 4 is a front elevational view thereof in a flattened
position.

FIG. 5 is a right side elevational view thereof.

FIG. 6 is a rear elevational view thereof.

FIG. 7 is a top plan view thereof.

FIG. 8 is a bottom plan view thereof.
